UNITED STATES PATENT OFFICE.

AUGUST THONET, OF VIENNA, AUSTRIA-HUNGARY.

DESIGN FOR A CHAIR.

SPECIFICATION forming part of Design No. 22,998, dated January 2, 1894.

Application filed December 7, 1893. Serial No. 493,047. Term of patent 7 years.

To all whom it may concern:

Be it known that I, AUGUST THONET, a subject of the Emperor of Austria-Hungary, residing at Vienna, Austria-Hungary, have invented and produced a new and original Design for Chairs, of which the following is a specification.

In the accompanying drawing, a perspective view of a chair showing my new design is given.

The leading feature of my design consists in a chair having a segmental bar at the top of its back and an inverted U-shaped bar in the back, the ends of the shanks of the U-shaped bar resting against the side-bars of the back.

A is the seat, B the legs, C the braces, crossing each other below the seat, D a bead on the front edge of the seat, E the upper exten-

sions of the rear legs forming the side parts 20 of the back, and F a segmental top bar of the back. G is an inverted U-shaped bar, the top of which is some distance below the top segmental bar F, and the shanks of which rest against the sides of the back, a short distance 25 above the seat.

Having thus described my invention, I claim as new and desire to secure by Letters Patent—

The design for a chair, substantially as 30 shown and described.

In testimony that I claim the foregoing as my invention I have signed my name in presence of two subscribing witnesses.

AUGUST THONET.

Witnesses:

CARL ANDREAE,
DEAN B. MASON.
